FIG. 1 is a perspective view of a suction cleaner showing my new design;

FIG. 2 is a side view;

FIGS. 3 and 4 are top and bottom plan views, respectively, of the cleaner shown in FIG. 1;

FIGS. 5 and 6 are end views;

FIG. 7 is a perspective view of another suction cleaner embodying my new design;

FIG. 8 is a side view;

FIGS. 9 and 10 are top and bottom plan views, respectively, of the cleaner shown in FIG. 7;

FIGS. 11 and 12 are end views;

FIG. 13 is a perspective view of still another suction cleaner embodying my new design;

FIG. 14 is a side view;

FIGS. 15 and 16 are top and bottom plan views, respectively, of the cleaner shown in FIG. 13; and FIGS. 17 and 18 are end views.

The sides of the cleaners opposite from the sides thereof shown in FIGS. 2, 8 and 14, have the same ornamental appearance as the sides shown in FIGS. 2, 8 and 14.

I claim:

The ornamental design for a suction cleaner, substantially as shown and described.
